(57) **CLAIM**

I claim the ornamental design for a mobile phone, as shown and described.

DESCRIPTION

FIG. 1 is a top perspective view of a mobile phone of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a top perspective view thereof shown in a closed position; and,

FIG. 9 is a front perspective view thereof shown in an alternate opened position.

The broken line showing of the keypad, display, and speaker in FIG. 1, 2, 7, and 9, which are immediately adjacent to the claimed subject matter and define non-shaded regions, represent the bounds of the claimed design, while all other broken lines are directed to environment and are for illustrative purposes only; the broken lines form no part of the claimed design.
